US00D895681S

(12) **United States Design Patent** (10) Patent No.: **US D895,681 S**
(45) Date of Patent: ** Sep. 8, 2020

(54) **DISPLAY SCREEN WITH ICON**(71) Applicant: **King.com Limited**, St. Julians (MT)

(72) Inventors: **Renato Roldán Ramis**, Barcelona (ES);
Diego Montes Guzmán, Barcelona (ES); **Lidia Morales Estevez**, Barcelona (ES); **Humberto Muret Deudero**, Barcelona (ES); **Maria Pérez Gago**, Barcelona (ES); **Mathieu Delaruelle**, Barcelona (ES); **Maria Esther López Rodriguez**, Barcelona (ES); **Óscar Gaya Belles**, Barcelona (ES); **Julio López Cruz**, Barcelona (ES); **Miquel Gelabert Reus**, Barcelona (ES); **Lucià Riba Gali**, Barcelona (ES); **Isaac Castilla Morales**, Barcelona (ES)

(73) Assignee: **KING.COM LIMITED**, St. Julians (MT)

(**) Term: **15 Years**

(21) Appl. No.: **29/637,177**

(22) Filed: **Feb. 14, 2018**

(30) **Foreign Application Priority Data**

Sep. 26, 2017 (EM) 004372472

(51) LOC (12) Cl. **14-04**

(52) U.S. Cl.

USPC **D14/494**; D14/495

Primary Examiner — Darlington Ly

Assistant Examiner — Katherine A Holbrow

(74) Attorney, Agent, or Firm — Arent Fox LLP

(57) **CLAIM**

The ornamental design for a display screen with icon, as shown and described.

DESCRIPTION

The design patent application file contains at least one drawing executed in color. Copies of this design patent application publication with color drawing(s) will be provided by the Office upon request and payment of the necessary fee.

The FIGURE is a front view of a display screen with icon showing our new design.

The broken line showing the remainder of the display screen and the remainder of the device is for environmental purposes only and forms no part of the claimed design.

**1 Claim, 1 Drawing Sheet
(1 of 1 Drawing Sheet(s) Filed in Color)**
